UNITED STATES PATENT OFFICE.

JOHN HONECKER, OF CLEVELAND, OHIO.

DESIGN FOR A HAT-RACK.

SPECIFICATION forming part of Design No. 21,781, dated August 23, 1892.

Application filed June 6, 1892. Serial No. 435,756. Term of patent 7 years.

To all whom it may concern:

Be it known that I, JOHN HONECKER, a citizen of the United States, residing at Cleveland, Cuyahoga county, Ohio, have invented and produced a new and original Design for Hat and Coat Racks, of which the following is a specification, reference being had to the accompanying drawing by letters of reference, forming part of this specification.

10 The drawing represents a perspective view of my rack.

The drawing represents a perspective view of a rack. The rack is like a rectangular frame, having its lower part A wider than its 15 ends C and beveled on its upper edge, and its top D, as shown, curves down on its upper

edge from center to ends and is suitably ornamented, so as to secure the attractive appearance of the whole rack, and in front and parallel with the lower edge of part D lies a 20 rod E between forwardly-projecting parts F at the ends of the rack.

What I claim is—

The design for a hat-rack, substantially as herein shown and described. 25

In testimony that I claim the foregoing as my own I affix my signature in presence of two witnesses.

JOHN HONECKER.

Witnesses:

FRANK W. WAGNER,
CHAS. HONECKER.
